US0D1019023S

(12) **United States Design Patent** (10) Patent No.: **US D1,019,023 S**
(45) Date of Patent: ** Mar. 19, 2024

(54) **COLLAR ATTACHMENT OF A CASE FOR AN ELECTRONIC DEVICE**

(71) Applicant: **Amazon Technologies, Inc.**, Seattle, WA (US)

(72) Inventors: **Michael Edward James Paterson**, San Francisco, CA (US); **Chia-Wei Chan**, New Taipei (TW); **Mei Hsuan Chen**, Seattle, WA (US); **Benjamin Wild**, Seattle, WA (US); **Matthew J. England**, Santa Monica, CA (US); **Wen-Yo Lu**, Pasadena, CA (US); **James Siminoff**, Pacific Palisades, CA (US); **Mark Siminoff**, Mountain View, CA (US); **Yen-Chi Tsai**, New Taipei (TW)

(73) Assignee: **Amazon Technologies, Inc.**, Santa Monica, CA (US)

(**) Term: **15 Years**

(21) Appl. No.: **29/729,753**

(22) Filed: **Mar. 30, 2020**

Related U.S. Application Data

(63) Continuation of application No. 29/706,458, filed on Sep. 20, 2019, now Pat. No. Des. 955,251.
